SHELVING CONSTRUCTION

Ernest R. Erickson, Des Moines, Iowa, assignor to
 C. E. Erickson Company, Incorporated, Des
 Moines, Iowa, a corporation of Iowa

Application December 26, 1939, Serial No. 310,997

3 Claims. (Cl. 211—148)

My invention involves a construction for the convenient assembly of standardized elements into shelving suitable for storage or display purposes.

An object of my invention is to provide a construction such that the component elements can be cheaply and conveniently packed and shipped in disassembled condition.

Another object is to provide a construction whereby the various elements can be easily and simply assembled at the point of use without tools or other auxiliary apparatus.

Another object is to provide a construction wherein the separate shelves in a shelving assembly can be located at various vertical heights as convenience or choice may dictate.

Another object is to provide a construction wherein additional sections can be added with a minimum of inconvenience and expense.

A further object is to provide a construction which is clean-cut and attractive in appearance so that it can be used for effective point-of-sale display of merchandise.

Another object is to provide a construction, the members of which can be easily and economically manufactured.

With these and other objects in view, my invention consists in the construction, arrangement and combination of the various parts of my device whereby the objects contemplated are attained, as hereinafter more fully set forth, pointed out in my claims and illustrated in the accompanying drawing, in which:

Figure 1 is a front perspective view of a section of shelving embodying the construction which I have devised. One complete section is shown in the figure and broken portions of a second section are shown attached to the right hand end of the first section.

Figure 2 is an enlarged fragmentary view, partly in vertical section, taken on the line 2—2 of Figure 1.

Figure 3 is an enlarged fragmentary view, partly in horizontal section, taken on the line 3—3 of Figure 2.

In the accompanying drawing I have used the reference numeral 10 to indicate generally a support member, which is preferably formed from sheet metal in the shape of a channel having a web 12 and flanges 14, as seen in the cross sectional view of Figure 3. This channel may be formed longitudinally in any desired manner. I have shown it as made with a straight rear portion 16 and a front portion 18 having an offset 20 which permits the accommodation of two

15 sizes of shelves. At the top, the portions 16 and 18 are connected by a vertical portion 22. If desired, the portions 16, 18 and 22 may be made up from a single piece of channel, formed in a manner well understood in the art, or they may be made separately, and fastened together in any suitable way. At the bottom, members 16 and 18 are spaced and strengthened by a stretcher 24, which I form of a similar channel fitting 20 within and spot welded to the bottom ends of the members 16 and 18. Any suitable form of rigid spacing means can be used in place of the stretcher 24. In the flanges 14 of the members 16 and 18 I punch perforations 26, preferably in 15. the form of vertically elongated slots.

I provide shelves 28 formed of sheet metal or any other suitable material and in any desired shape. In the drawing I have shown the shelves 28 as having an up-turned rear wall 30 and a downturned front wall 32. These walls constitute flanges along the front and back edges of the shelf adding materially to the strength of it. The rear wall 30 may be provided with a rolled or folded edge 33. End walls 34 may be provided if desired. At the ends of the rear wall 30 I provide projecting hook-like portions 36 and notches 38. The portions 36 are adapted to pass through the perforations 26 in the support members 16 and 18. After the portions 36 are passed 30 through the perforation, the shelf 28 is pressed downwardly to cause the notches 38 to engage the flanges 14. I preferably form the notches 38 at a slight angle from the vertical, with the top of the notch inward as will be seen in Figure 35 2, in order to cause a wedging effect whereby the shelf 28 is held tightly against the channel member 10.

A similar hook and slot engagement is provided between the front wall 32 of the shelf 28 and the front support member 18. A portion of the right hand member 18 has been broken away in Figure 1 to show this construction.

When several shelves are assembled with the support members in the manner contemplated in 45 my invention, great rigidity is obtained by reason of the wedging action in the inclined notches 38 against the flanges 14. Any load applied on the shelves tends to tighten the fit thus obtained and to increase the rigidity of the structure.

50 As will be seen, particularly in Figure 1, a series of the perforations 26 is provided vertically spaced along the support members 16 and 18. This permits a given shelf 28 to be mounted at practically any height, as may be desired for most attractive appearance of the assembled

structure or for the most efficient storage or disposition of goods upon the shelves. Any required number of shelves can be incorporated at the time of assembly.

By the use of a support member having an off-set, as at 20, shelves of several front-to-back depths can be accommodated. Where by structure is used for display purposes, as in a grocery store, this arrangement allows for the fact that visibility of the goods on the bottom shelf is poor, unless this shelf is wider. Furthermore, the increased width of the structure at the bottom obviously gives greater stability.

By reason of the fact that perforations 26 are provided in both flanges 14 of the channel, the shelving assembly can be extended from either side by the use of additional shelf members, such as 28. In Figure 1 the right-hand portion of the figure shows broken parts of such shelves. A single support member 10 thus forms a common support for two sections of shelving and a very economical arrangement is secured.

The shelves 28 may be made up in various widths, and obviously adjacent tiers of shelves as assembled need not be of the same width. Tiers of several widths may be used in one shelving installation if necessary in order to "come out even," for example, when it is desired to have the shelving fill a given wall space or a given horizontal distance.

It will be apparent that in making shipment of the elements of my construction in disassembled condition, the supports 10 can be stacked or bundled in small space, and likewise the shelves such as 28 can be stacked in relatively small space. Hence, a shelving assembly which occupies a very considerable amount of space when set up, can be packed, shipped or stored in a space which is relatively much smaller.

Some changes may be made in the construction and arrangement of the parts of my device without departing from the real spirit and purpose of my invention, and it is my intention to cover by my claims any modified forms of structure, or use of mechanical equivalents, which may be reasonably included within their scope.

I claim as my invention:

1. In a display structure, supporting members having front and rear elements, shelf members having an upstanding back flange, a depending front flange and a web element spanning the dis-

tance between the lower edge of said back flange and the upper edge of said front flange, and means for detachably attaching said shelf members to said supporting members comprising downwardly extending hooked lugs formed as integral extensions of the ends of said flanges, said supporting members having a series of vertically spaced and vertically elongated openings to receive said lugs with the lugs of said front flange below said web element and the lugs of said back flange above said web element, said lugs having surfaces adjacent the ends of said flanges which are inclined downwardly and away from said ends.

2. In a display structure, supporting members having front and rear elements, shelf members having an upstanding back flange, a depending front flange and a web element spanning the distance between the lower edge of said back flange and the upper edge of said front flange, and means for detachably attaching said shelf members to said supporting members comprising downwardly extending hooked lugs formed as extensions of the ends of said flanges, some of said lugs being located at a higher elevation than said web element and some of said lugs being located at a lower elevation than said web element, said supporting members having a series of vertically spaced and vertically elongated openings to receive said lugs, said lugs having surfaces adjacent the ends of said flanges which are inclined downwardly and away from said ends, said shelf elements having upstanding flanges at the ends thereof to span the distance between the front and rear elements of said frame members.

3. A display structure including a shelf member having a web element with an upstanding flange along one edge thereof and a depending flange along the opposite edge thereof, supporting members, and means for detachably attaching said shelf member to said supporting members comprising downwardly opening hooked lugs formed at the ends of said flanges, said supporting members having openings to receive said lugs with the lugs of said upstanding flange above the line of connection of said upstanding flange with said web element, the lugs of said depending flange below the line of connection of said depending flange with said web element.

ERNEST R. ERICKSON.
